(57) **CLAIM**

The ornamental design for an upper cap for a liquid dispensing syringe, as shown and described.

DESCRIPTION

FIG. 1 is a perspective view of an upper cap of the liquid dispensing syringe according to the invention.

FIG. 2 is a front elevation view thereof with the rear elevation view being a mirror image thereof.

FIG. 3 is a right side elevation view thereof with the left side elevation view being a mirror image thereof.

FIG. 4 is a top plan view thereof; and,

FIG. 5 is a bottom plan view thereof.

The broken lines in the figures are shown for the purpose of illustrating boundaries of the claimed design and the areas inside the broken line boundaries form no part of the claimed design.
